CLIP FOR A WRITING INSTRUMENT OR THE LIKE

Robert W. Schier, Evanston, Ill., assignor to The Parker Pen Company, Janesville, Wis., a corporation of Wisconsin

Filed Oct. 23, 1958, Ser. No. 53,121

Term of patent 14 years

(Cl. D74—2)

FIG. 1 is a front elevational view of a clip for a writing instrument or the like embodying my new design;

FIG. 2 is a side elevational view thereof as seen from the right of FIG. 1;

FIG. 3 is a top plan view looking in the direction of the arrows 3—3 of FIG. 1; and

FIG. 4 is a bottom plan view looking in the direction of the arrows 4—4 of FIG. 1.

I claim:

The ornamental design for a clip for a writing instrument or the like, as shown.
